CLAIM

(21) Appl. No.: **29/876,415**

The ornamental design for a multi-compartment storage bag with rounded corners, as shown and described.

(22) Filed: **May 22, 2023**

DESCRIPTION

Related U.S. Application Data

(62) Division of application No. 29/711,740, filed on Nov. 1, 2019.

FIG. 1 is a top, front perspective view of a first embodiment of the multi-compartment storage bag with rounded corners, showing my new design;

(51) **LOC (14) Cl.** **09-05**

FIG. 2 is a rear elevational view thereof;

(52) **U.S. Cl.**

FIG. 3 is a top plan view thereof;

USPC **D9/709; D3/273**

FIG. 4 is a bottom plan view thereof;

(58) **Field of Classification Search**

FIG. 5 is a left side elevational view thereof;

USPC D3/273, 276, 285, 287, 283, 289, 301,

FIG. 6 is a right side elevational view thereof;

D3/901, 903, 206; D9/709

FIG. 7 is a top, front perspective open view of the first embodiment;

CPC A47G 29/08; A47J 45/02; A45C 11/008;

FIG. 8 is a top, front perspective view of a second embodiment of the multi-compartment storage bag with rounded corners, showing my new design;

A45C 5/005; A45C 13/002; A45D 44/18

FIG. 9 is a rear elevational view thereof;

See application file for complete search history.

FIG. 10 is a top plan view thereof;
